(57) **CLAIM**

The ornamental design for a toilet brush, as shown and described.

DESCRIPTION

FIG. 1 is a first perspective view of a toilet brush showing my new design;

FIG. 2 is a second perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an exploded perspective view thereof; and,

FIG. 10 is an enlarged view of the selected portion 10 in FIG. 1.

The evenly spaced broken lines immediately adjacent to the shaded areas depict the bounds of the claimed design, while all other broken lines are directed to environment. In addition, the dot-dash broken lines depict the bounds of the enlarged views and form no part of the claimed design.

1 Claim, 10 Drawing Sheets
